UNITED STATES PATENT OFFICE.

JENNIE M. BODENSIEK, OF NEW YORK, N. Y.

HOSE-SUPPORTER CLASP.

Application filed August 8, 1925. Serial No. 48,919.

Heretofore, hose supporter clasps have had the disadvantage that they are either insecure or cause a drop stitch in the hose, especially in the finer silk hose.

5 My invention has for its object to overcome these disadvantageous features of the clasps now in use, and to provide a clasp the use of which does not cause drop stitches, and at the same time securely holds the hose 10 in position.

For this purpose, my invention consists in providing a ribbed base of the usual rubber or like material, and subjecting this rib of the base to lateral spring pressure, the 15 hose being interposed between lateral sides of the rib and the springs, the usual button on the base having a relatively free play in the enveloping yoke, being however limited in its movement by the lateral springs. In 20 one embodiment the spring is held within the yoke at one end thereof and passing out of the yoke forms the clasping portion, and then has its free ends enter again into the yoke, being therein freely movable. Preferably also the inner surface of the yoke is 25 rounded and smooth, and does not provide sharp edges in the nature of cutting edges acting against the hose and button on the base as heretofore. The holding pressure 30 being therefore distributed, the strains and stresses to which the hose is subjected are also distributed. This distribution of pull avoids a pull on any particular stitch of the 35 hose and thus avoids the causation of the drop stitch. Moreover, the hose instead of being held substantially only at one spot, is held along a considerable part of the same in view of the folding and lapping of the 40 hose over the button and the rib of the base. By this folding and lapping, both a transverse and longitudinal hold on the hose 45 is secured.

The invention embodies further features 45 of novelty, which will be pointed out hereafter.

The invention, as also embodiments thereof, will be described hereinafter, shown in the drawings, and finally pointed out in the 50 claims.

50 In the accompanying drawings,—

Figure 1 is a front view of an embodiment 55 of my invention;

Figure 2 is a side view of the same;

Figure 3 is a section on line 3—3 of Figure 1;

Figure 4 is an enlarged front view of the yoke portion and spring;

Figure 5 is a vertical section on line 5—5 of Figure 4;

Figure 6 is a horizontal section on line 60 6—6 of Figure 4;

Figure 7 is a front view of the base having the rib and button;

Figure 8 is a side view thereof; and

Figure 9 is section similar to that of 65 Figure 3, but showing the hose held in position.

Similar characters of reference indicate corresponding parts throughout the various 70 views.

Referring to the drawings, the usual garter ribbon 10 is secured to the metallic loop 11, which in turn is connected with the loop 12 end 12 of the yoke 13. The yoke 13 is made of suitable metal. The base 14 is hingedly 75 connected with the part 12 and has the button 15 thereon adapted to engage the lower end of the yoke. In general the parts described are old and well known.

The yoke however is made tubular and 80 within the tube is arranged the closed end of a bent spring 17, having this closed end 18 within the lower part of the tubular yoke portion 19 as clearly seen in Figure 5. The spring 17 then has its symmetrical members 85 pass out of openings 20 of the tubular yoke, and converging towards its narrowest proximity to form jaws 21, these members then diverge towards the yoke the free end of each enters its respective opening 22 of the 90 yoke. The free ends are bent back as at 23 so as to glide on the shell of the tubular yoke, and ride on the wall 24 thereof.

The base 14 is formed with the button 15, and a rib 25 which extends outwardly therefrom a distance substantially equal to the height of the stem 26 of the button, and is of a thickness substantially equal to the thickness or diameter of the stem of the button. The sides of the rib are substantially 100 parallel, and the base, button and rib are of suitable flexible material such as rubber, or the like. The rear of the base is backed by a fabric lining 27 which serves to reinforce the base and protect the skin of the wearer 105 against abrasion.

The operation is as follows:

The base 14 with its button 15 and rib 25, is hinged to the loop end of the yoke 13, and is disengaged therefrom. The base 110

is placed below the hose and then the yoke 13 with its spring 17 is moved longitudinally thereup, whereby the button 15 with its covering hose enters the narrowest space 21 of the spring members and slightly presses them apart and then the button with its covering hose gradually enters the enclosed opening surrounded by the springs and yoke portion 29, as the button with its covering of hose thus moves, the spring members press against the hose covering the rib 25. The button then centers in position having a certain amount of free play in the confined space in the lower portion 29, but it cannot move back because of the action of the spring pressing against the sides of the rib. The hose also extends over the inclined portion 30 of the rib 25 and to some extent is held thereon.

20 Thus the hose is held by the yoke portion 29 and button 15, by the rib 25 and spring 17, and by the shoulder 30. The manner in which the hose 31 is held by the spring and rib is shown in Figure 9.

25 In the use of my improved device only two points of contact are provided namely, along the sides of the rib, and that is a longitudinal contact which is less likely if not impossible, to cause a lock stitch. Also the hose will be kept in alignment, and the clasp will not twist. All parts are rounded and no contacting parts are sharp edged. All these advantageous features prevent not alone the safeguarding of the hose but also prevent the underwear from being torn.

30 I have described an embodiment of my invention, but it is clear that changes may be made therein without departing from the spirit of the invention as defined in the appended claims.

40 I claim as new:

45 1. A hose supporter clasp comprising a base having a button and a rib thereon, a yoke movably mounted with respect to said base and having an interior wedge-shaped slot for receiving said button and rib, and yieldable means carried by said yoke projecting from both sides of the yoke into the intermediate portion of the wedge-shaped slot and against opposite sides of said rib, said rib adapted to force the material received in said hose supporter into a bight, said yieldable means acting to hold the sides of the bight forming portions of the material against the sides of said rib to bind the material tighter, said yoke acting to hold the material tightly against the face of said base.

55 2. A hose supporter clasp comprising a

base having a button and a longitudinal rib 60 projecting therefrom, a yoke movably associated with said base and having an interior closed wedge-shaped slot for receiving said button and rib, said yoke being tubular and having spaced openings in its interior side walls, a piece of spring wire having its intermediate portion disposed in the lower part of the yoke, its sides extending in bowed condition out through the lower openings and into the upper openings of 70 said interior side walls, said bowed portions acting yieldably upon opposite sides of said rib, the extremities of said spring wire entering the upper openings in the interior side walls and sliding yieldably against the 75 opposite exterior side walls of the yoke member.

3. A clasp comprising a base having an outstanding rib and a headed part, a yoke 80 movably associated with the base and having a wedge slot receivable about said rib and headed part, and yieldable means carried by said yoke and movable relatively to the yoke and positioned for engagement with the sides of the rib.

4. A clasp comprising a base having a long rib and a headed part adjoining the rib, a yoke movably associated with the base and having a wedge slot to receive the rib and headed part, and yieldable means carried by and movable relatively to said yoke, said yieldable means having portions spaced from said yoke for flexing in the plane of the yoke towards and from the sides of said rib and in directions angular to the plane 95 of said yoke toward and from the base.

5. A clasp comprising a base, an outwardly extending rib on said base, said rib having parallel sides, a button at one end of the rib, a yoke movably associated with 100 the base and yieldable means movably associated with the yoke, said yieldable means including jaws for yieldably engaging the parallel sides of the rib in spaced relation to the button.

105 6. A clasp comprising base, a rib on said base, a button at one end of the rib, a yoke having a U-shaped tubular body formed in its inner wall with oppositely disposed openings and yieldable means movably contained within the yoke including jaws projecting through the openings in the yoke for yieldably engaging the sides of the rib in spaced relation to the button.

110 In testimony that I claim the foregoing as my invention, I have signed my name hereto.

JENNIE M. BODENSIEK.
